SEARCHLIGHT CONTROL SYSTEM

Donald A. Youngson and Robert E. Matthews,
Devon, Conn., assignors to General Electric
Company, a corporation of New York

Application September 25, 1946, Serial No. 699,250

7 Claims. (Cl. 314—40)

1

Our invention relates to light projectors of the arcing electrode type, and more particularly to control systems for arc searchlights and the like. The invention is especially applicable to searchlights wherein quick starting or arc initiation is desired, as in searchlights used on aircraft or for aircraft observation.

In the operation of arc light projectors it is customary to advance the negative electrode until it makes contact with the positive electrode, and thereupon to withdraw the negative electrode to strike the arc. Time may be saved in this operation if the electrodes are brought into engagement immediately upon extinguishing the arc and allowed to remain in engagement until the next arc striking operation. Arc striking then is accomplished simply by withdrawing the negative electrode.

Accordingly it is a general object of our invention to provide new and novel control means for arc light projectors.

It is a further object of our invention to provide a low voltage quick starting electrode feed circuit for arc light projectors which is entirely independent of the normal high voltage source of arc current supply.

It is a more particular object of our invention to provide new and novel means for automatically engaging the electrodes of an arc light projector immediately upon deenergization of the arc, so that the arc can be struck quickly and simply by energizing and subsequently separating the electrodes.

In carrying out our invention we provide a pair of arcing electrodes connected to a high-voltage source of electric current supply. For feeding or positioning these electrodes in accordance with certain arc characteristics, we provide control means including an electric feed motor which is energized during arcing operation from a low voltage source of electric current supply. In order to move the electrodes into engagement immediately upon extinguishment of the arc to prepare the projector for quick starting operation, we provide switching means operable to connect the low voltage current supply source to the electrode feed motor through an alternative circuit when the arc current supply is disconnected. During such connection of the feed motor, the low voltage source is also connected to the electrodes in order to detect engagement thereof and thereupon to disconnect the feed motor.

For a more complete understanding of our invention, reference should now be had to the fol-

2

lowing detailed specification along with the accompanying drawing, the single figure of which is a schematic circuit diagram of an arc electrode control system embodying our invention.

Referring now to the drawing, we have shown an arc searchlight comprising a positive electrode 1 and a negative electrode 2 arranged to be connected through a contact 3 of a line contactor 4 to the corresponding terminals of a suitable source of high voltage electric current supply, such as a 60 volt direct current generator 5. The line contactor 4 is provided with an actuating winding 6 arranged to be energized from a low voltage source of control power, such as a 24 volt line 7, through a cut-out switch 8, a selector switch 9, and a pair of normally closed contacts 10 of a relay 11. The switch 9 closes on a stationary contact 12 in its operating position and on a stationary contact 13 in its standby position. The negative electrode 2 is supported by a pair of driving rollers 14, 15 and a pair of spring pressed electric conducting guide brushes 16, 17. Current is supplied to the electrode 2 through the brushes 16, 17, as shown, and the roller 15 is serrated and driven by a negative drive motor 18, thereby to advance or retract the electrode 2. The drive motor 18 is provided with a normally engaged magnetic brake 19 and a pair of oppositely wound series field windings 20 and 21. The magnetic brake 19 is arranged to be disengaged upon energization of the motor 18 by a brake coil 22 connected in series circuit relation in the motor circuit. The series field windings 20 and 21 are arranged to be alternatively connected to the source of control power 7 through the switches 8 and 9 and a current regulator 23. The regulator 23 comprises a current responsive actuating winding 24, a pair of normally closed contacts 25 and a pair of normally open contacts 26. The winding 24 is connected in series circuit relation in the arc circuit of the electrodes 1 and 2. The contacts 25 and 26 are controlled by a bridging contact 27. The motor 18, when energized through the series field winding 21, is arranged to drive the electrode 2 in a forward direction toward the electrode 1. The motor field winding 20, when energized, causes the motor 18 to operate in the opposite direction, thereby to retract the electrode 2. The field winding 20 is energized through the regulator contacts 26 only when the current through the arc and thus through the regulator coil 24 exceeds a predetermined maximum value.

The positive electrode 1 is arranged for continuous rotation and forward feed alternatively

at one or the other of two selectable speeds. For this purpose the electrode 1 is mounted in a rotatable head 28 which is journaled in a fixed support 29. The head 28 comprises a hollow sleeve 30 within which the electrode 1 is slidably loosely. The sleeve 30 carries at one end a gear bracket 31. Within the gear bracket 31 the electrode 1 is supported between a guide roller 32 and a serrated or toothed driving roller 33. The electrode 1 is further guided and also supplied with current by a pair of spring pressed electric conducting sliders 34 and 35. The shaft of the driving roller 33 carries also a driving pinion 36. The pinion 36 meshes with a worm gear 37 journaled at 38 in the rotatable head bracket 31. The shaft of the worm gear 37 carries at its opposite end a planetary spur gear 39 which meshes with a sun gear 40 journaled in the frame 29 and rotatable with respect to the electrode head 28. Specifically the sun gear 40 is attached to a rotatable hollow sleeve 41 which is journaled in the frame 29. On the sleeve 41 adjacent the pinion 40 there is mounted a spur gear 42. The hollow sleeve 30 forming part of the rotatable head 28 is rotatably journaled within the sleeve 41. At the end of the sleeve 30 remote from the gear bracket 31 there is mounted a spur gear 43 fixed to the sleeve 30 by a setscrew 44. The spur gear 43 is of slightly greater diameter than the spur gear 42. Finally, the gears 42 and 43 are simultaneously and continuously driven by a pair of pinions 45 and 46. The pinions 45 and 46 are journaled in the frame 29 and connected, as by a shaft 47 (indicated schematically), to a driving motor 48. The pinion 46 is slightly smaller than the pinion 45, so that the spur gear 42 is driven faster than the gear 43. It will of course be understood that, if desired, the gear 42 may be driven slightly slower than the gear 43, it being only necessary that the gears 42 and 43 be driven at unequal speeds. It may be noted however, that if the speed relationship is reversed from that shown, it is also necessary to reverse the direction of rotation of the motor 48 so that the electrode 1 will advance.

It will be observed that in the operation of the positive electrode driving mechanism, the spur gear 43 driven by the motor 48 and attached to the electrode head 28 rotates the electrode head about its own axis, thereby continuously to rotate the electrode 1. If, now, the spur gear 42 were not driven, but were allowed to rotate idly upon the sleeve 30, it would be carried around by the supporting head 28 and the gears 36, 37 and 39 at the same speed as the head, so that the gears 37 and 39 would not rotate upon their own axis and therefore would not drive the electrode 1 longitudinally. In fact however the spur gear 42 is positively driven by the pinion 45 at a speed slightly greater than the speed of the head 28 itself. Thus, the planetary gear 39 is caused to roll slowly around the sun gear 40, thereby to rotate the worm gear 37 on its own axis and continuously to drive the positive electrode 1 forward as it rotates. As will be explained more fully hereinafter, the crater in the end of the positive electrode 1 is maintained in a predetermined desired position by providing two selectable driving speeds for the positive head mechanism in conjunction with a control system responsive to crater position, as described and claimed in copending application Serial Number 699,287, filed September 25, 1946, by Robert C. Sheahan, and having the same assignee as this application, which has become U. S. Patent 2,440,122, dated April 20, 1948.

During normal arcing operation, the positive driving motor 48 is connected to the low voltage source of control power 7 through the manually operable cut out switch 8 and the selector switch 9. The motor 48 is provided with a shut field winding 49. For control of the speed of the motor 48 there is connected in series with the motor armature a variable resistor 50 which is arranged to be shunted by a thermally responsive switch 51. The switch 51 is closed when cold, and opens its contacts when hot to insert the resistor 50 in the motor armature circuit.

The thermally responsive switch 51, and thus the speed of the motor 48, is controlled in accordance with the position of the crater in the end of the electrode 1. This control may conveniently be effected by any well known optical system, such as that described in U. S. Patent 1,590,543, issued on June 29, 1926, to Martin L. Patterson, and entitled "Feed control means for arc lights." Briefly such a system comprises an optical arrangement for reflecting the image of the positive crater directly upon the thermal responsive member 51 when the crater is in the desired position. In this position of the crater, then, the switch 51 is held open and the motor 48 operates at its low speed. If, however, the crater burns back farther than desired, the image of the crater moves off of the thermal responsive member 51, the member 51 closes its contact, and the speed of the motor 48 is increased, thereby to drive the electrode 1 forward at a greater speed.

As previously stated, means are provided for driving the electrodes 1 and 2 into contact immediately upon deenergization of the arc between the electrodes, thereby to prepare for the next arc striking operation. For this purpose, means are provided for connecting the electrode driving motors 18 and 48 to the low voltage source of control power 7 through alternative circuits when the selector switch 9 is in its stand-by position on the contact 13. In this position of the selector switch a circuit is also completed for applying control potential from the source 7 to the electrodes 1 and 2 so that, when the electrodes come into contact, a driving motor disabling circuit is completed.

Referring more particularly to the drawing, it will be observed that, when the selector switch 9 is in its stand-by position on the contact 13, a circuit is completed through the switches 8 and 9 from the control power source 7 to an actuating winding 52 of the relay 11. In parallel circuit relation with the winding 52 there is also a green indicating lamp 53 which is lighted in the stand-by position of the switch 9. It is desirable to provide also a red indicating lamp 54 which is lighted from the control power source 7 so long as the cutout switch 8 is closed. Thus, the lamp 54 only is lighted during arcing operation, while the lamps 53 and 54 are lighted in the stand-by condition.

When the relay 11 picks up, it first opens its contact 10, thereby to deenergize the contactor actuating winding 6 and to ensure drop-out of the high voltage line contactor 4. Thus, disconnection of the high voltage generator 5 from the electrodes during stand-by or quick starting operation is assured. Upon energization, the relay 11 also closes three pairs of normally open contacts 55, 56, and 57. The contacts 55, when closed, complete an alternative energizing circuit for the driving motors 18 and 48. This circuit may be followed from the control power source 7 through the cutout 8, the selector

switch 9 in its stand-by position, a normally closed contact 58 of a relay 59, and the relay contact 55 to the driving motors in parallel circuit relation. The relay contacts 56 and 57, when closed, prepare an energizing circuit for an actuating winding 60 of the relay 59 through the electrodes 1 and 2. This circuit may be followed from the source of control power 1 through the cutout switch 8, the selector switch 9 in its stand-by position, the relay contacts 57, the electrode 1, the electrode 2, the relay contacts 56, and the actuating winding 60 of the relay 59 back to the control power source 1. This latter circuit, of course, is not completed until the electrodes 1 and 2 come into engagement.

With the foregoing description of the various elements of our system and their individual mode of operation, the operation of the system as a whole will now be readily understood from the following brief description.

To consider first normal arcing operation, let it be assumed that the electrodes are separated as illustrated, and that the cutout switch 8 is closed and the selector switch 9 placed in its operating position on the contact 12. With the switch 8 closed the red indicating light 54 is energized. Through the switch 8 and the contact 12 of the switch 9 circuits are completed for the driving motors 18 and 48 in the manner previously described, the circuit for the negative drive motor 18 passing through the bridging contact 27 of the regulating relay 23. In parallel circuit relation with the motors, there is also completed an energizing circuit for the actuating winding 6 of the line contactor 4. This energizing circuit includes the normally closed contact 10 of the relay 11. Accordingly, therefore, as soon as the switch 8 is closed and the switch 9 placed in its operation position, the driving motors 18 and 48 are placed in operation and the line contactor 4 is picked up to apply arcing voltage to the electrodes from the generator 5.

Since no arc exists, the regulator contacts 25 are closed and the negative driving motor drives the electrode 2 forward into engagement with the electrode 1. The electrode 1, of course, is simultaneously being driven forward at its maximum speed because the thermal responsive member 51 is cold. When the electrodes 1 and 2 come into contact, the resulting high current flow picks up the regulating relay 23, opening contacts 25 and closing contacts 26, thereby reversing operation of drive motor 18, which withdraws electrode 2 from contact causing an arc to be struck between 1 and 2. With arcing taking place, the crater at the end of the positive electrode 1 is maintained in a predetermined position by operation of the thermal responsive member 51 and the motor 48, and the negative electrode 2 is advanced or retracted as required in order to maintain the arc current substantially constant.

When it is desired to extinguish the arc, the selector switch 9 is moved from its operating position on the contact 12 to its stand-by position on the contact 13. As soon as the contact 12 is disengaged, the normal operating circuit for the driving motors 18 and 48 is disabled and the actuating winding 6 of the high voltage line contactor 4 is deenergized. However, as soon as the selector switch 9 is placed upon the stand-by contact 13, an energizing circuit is completed for the actuating winding 52 of the relay 11. When the relay 11 picks up, a new energizing circuit is completed for both electrode driving

motors 18 and 48 through the contact 58 of the relay 59 and the contact 55 of the relay 11. Simultaneously, control potential is applied to the electrodes 1 and 2 through the actuating winding 60 of the relay 59 and the contacts 56 and 57 of the relay 11 as heretofore described. Accordingly, therefore, both electrodes are advanced until they come into engagement. As soon as the electrodes 1 and 2 are engaged, a circuit is completed through the electrodes for the actuating winding 60 of the relay 59. When the relay 59 is picked up, it opens its contact 58 thereby to deenergize both driving motors 18 and 48. Thus, in the stand-by position, the electrodes 1 and 2 remain in engagement and the relays 11 and 59 remain picked up, the relay 59 being energized from the low voltage control power source through the electrodes 1 and 2 themselves. Both indicating lamps 53 and 54 are lighted to indicate this condition.

It should be noted that, if desired, the green lamp 53 may be so connected that it will be lighted only when the electrodes 1 and 2 actually engage. If such indication is desired it is only necessary to connect the lamp 53 in series with the relay contacts 58, rather than as shown.

It will now be appreciated that in our new and improved system resetting of the electrodes for quick starting operation is carried out entirely at low voltage so that the system is entirely safe and free from danger of reinitiating the arc at undesired times. Disabling of the high voltage circuit is ensured by the selector switch 9, which, when placed in the reset position removes high voltage power from the electrodes.

While we have shown and described only a preferred embodiment of our invention by way of illustration, many modifications will occur to those skilled in the art and we therefore wish to have it understood that we intend in the appended claims to cover all such modifications as fall within the true spirit and scope of our invention.

What we claim as new and desire to secure by Letters Patent of the United States is:

1. In a light projector including a pair of arc-ing electrodes, means for connecting said electrodes to and disconnecting said electrodes from a source of high voltage electric current supply, electrode feed control means including an electric motor, means for connecting said motor to a source of low voltage electric current supply and simultaneously applying the potential of said low voltage source to said electrodes when said high voltage source is disconnected, said motor when so connected driving said electrodes toward engagement, and electrical means responsive to completion of a low voltage circuit by engagement of said electrodes for deenergizing said motor.

2. In a light projector including a pair of arc-ing electrodes, electrode feed control means including an electric motor, means for simultaneously connecting said electrodes to a source of high voltage electric current supply and connecting said motor to a source of low voltage electric current supply, separate means operable when said high voltage source is disconnected for connecting said motor to said low voltage source, and relay means operable from said low voltage source upon engagement of said electrodes to disconnect said motor from said low voltage source.

3. In a light projector including a pair of arc-ing electrodes, electrode feed control means including an electric motor, switching means for simultaneously connecting said electrodes to a

source of high voltage electric current supply and connecting said motor to a source of low voltage electric current supply, relay means operable by said switching means for connecting said motor to said low voltage source when said high voltage source is disconnected, and second relay means operative upon engagement of said electrodes when said first relay means is operated for disconnecting said motor from said low voltage source.

4. In a light projector including a pair of arcing electrodes, electrode feed control means including an electric motor connected to drive one of said electrodes toward engagement with the other, first switching means for connecting said electrodes to a source of high voltage electric current supply and simultaneously connecting said motor to a source of low voltage electric current supply to energize said motor, second switching means operable only when said first switching means is inoperative for connecting said motor to said low voltage source with said high voltage source disconnected and simultaneously applying said low source voltage between said electrodes, and electro-responsive means operable from said low voltage source upon engagement of said electrodes to disable said second switching means thereby to deenergize said motor with said electrodes in engagement.

5. In a light projector including a pair of arcing electrodes, means for connecting said electrodes to a source of high voltage electric current supply, electrode feed control means including an electric motor connected to drive one of said electrodes toward engagement with the other, means for connecting said motor to a source of low voltage electric current supply to energize said motor, and means responsive to engagement of said electrodes for rendering said low voltage connecting means ineffective, thereby to deenergize said motor with said electrodes in engagement.

6. In a light projector including a pair of arcing electrodes, means for connecting said elec-

trodes to a source of high voltage electric current supply thereby to maintain an arc between said electrodes, electrode feed control means including a reversible electric motor connected to drive one of said electrodes toward and away from the other, means for connecting said motor to a source of low voltage electric current supply to energize said motor, regulating means responsive to arc current for controlling said motor to maintain said current substantially constant, said regulating means controlling said motor to drive said electrodes toward engagement when said high voltage source is disconnected and said arc extinguished, and means responsive to engagement of said electrodes for rendering said low voltage connecting means ineffective thereby to deenergize said motor with said electrodes in engagement.

7. In a light projector including a pair of arcing electrodes, means for connecting said electrodes to a source of high voltage electric current supply, electrode feed control means including an electric motor connected to drive one of said electrodes toward engagement with the other, first switching means for connecting said motor to a source of low voltage electric current supply when said arc is operative, second switching means for connecting said motor to said low voltage supply source when said arc is inoperative, and means responsive to engagement of said electrodes for disabling said second switching means, thereby to deenergize said motor with said electrodes in engagement.
